RECUPERATOR CONSTRUCTION

Arthur W. Catlin, Manitowoc, Wis., assignor to Manitowoc Shipbuilding Company, Manitowoc, Wis.

Application December 23, 1954, Serial No. 477,170

2 Claims. (Cl. 263—32)

This invention relates to a recuperator construction for a rotary kiln and is particularly directed to a liner construction for the recuperator section of the kiln.

In kilns such as cement kilns, it is the usual practice to preheat the combustion air by blowing the incoming air through the hot clinkers adjacent the discharge end of the kiln to thereby quench the clinkers and preheat the air. It frequently happens that small fragments of clinkers found their way into the sub-frames forming the air ducts and, due to the liner plate construction previously used, were trapped in these ducts and plates and could not come out and, therefore, the ducts eventually became heavily loaded with particles.

In my prior Patent No. 2,477,287, of July 26, 1949, for Recuperator Construction, assigned to the same assignee as the present invention, I provided rectangular openings in the trailing sides of the grates or liners, mainly for the purpose of discharging clinker particles which had gathered either in an interior pocket of the liner or else in the air ducts. While this construction was a marked improvement over prior constructions it nevertheless had the defect of discharging air through the rectangular openings approximately tangentially of the recuperator. This produced a swirl in the flame and entrained coal dust, where pulverized coal was used, as well as clinker dust, thus obscuring the visibility in the kiln itself and also producing a scouring action which was not desirable, and further due to the suspended particles in the preheated air, causing abrasion and rapid wear of the primary air fan and other incidental equipment.

This invention is designed to overcome the above noted defects and objects of this invention are to provide a liner and recuperator construction in which tangential discharge of air is eliminated and instead in which the air is discharged radially of the kiln, in which there is markedly less accumulation of dust suspended in the cooling zone and in the preheated air, and in which there is a more uniformed depth of load on the liners, and in which the deep valleys between the liners are practically eliminated.

A further object of this invention is to provide a recuperator construction which provides for the elimination of clinker accumulation in the air ducts and in which the small particles of clinkers and clinker dust in the air ducts is constantly eliminated by blowing such particles outwardly through small slots or openings in the discharge end of the recuperator by means of the air blast, such discharged clinker particles joining the main load of the kiln at the discharge end of the kiln if so desired.

Further objects are to provide a liner construction in which improved cooling of the clinker results by reason of the fact that the finer particles in the clinker bed pass through the radially arranged slots thereby increasing the voids in the load in the recuperator section of the kiln in a substantially uniform manner which results in increase of air capacity of the liners or grates due to the distributed voids and also due to the fact that the

2

openings in the liners arranged in the radial manner provide in themselves an increased air capacity all of which produce favorable results and reduce the air pressure required for the recuperator unit.

5 Further objects are to provide better cooling of the bolts which anchor the liners to the outer shell thereby avoiding failure due to burning off the bolt heads which, in certain previous constructions, were in close proximity to the hot clinker, this invention differing from the prior 10 constructions by providing a construction of liner in which the bolt head is lowered into the air duct and is thereby effectively cooled by the air blast passing through the ducts.

An embodiment of the invention is shown in the accompanying drawings in which:

Figure 1 is a view looking directly down on a liner.

Figure 2 is a sectional view on the line 2—2 of Figure 1.

Figure 3 is a side view of the structure shown in Figure 1 with a part broken away and a part in section.

Figure 4 is an end view of the liner.

Figure 5 is a longitudinal, fragmentary, sectional view through a portion of the recuperator section of the kiln.

Figure 6 is a sectional view on the line 6—6 of Figure 5.

Figure 7 is a sectional view drawn on a reduced scale through a portion of the recuperator section of the kiln showing the clinker load and the manner in which the small clinker particles fall into the air passages.

30 Referring to the drawings it will be seen from Figures 5, 6 and 7, that the kiln is provided with an outer shell 10 of cylindrical shape to which a plurality of liners indicated generally by the reference character 11 are bolted by means of the bolts 12, spacing sleeves 13 being positioned between the transverse portion 14 of the liners and the outer shell 10 of the kiln. The ends of the liners rest upon longitudinally extending narrow strips 15 which are secured to supporting webs 16 of the recuperator section of the kiln as shown most clearly in Figure 6. It is 35 to be noted that the webs 16 are not directly secured to the outer shell 10 but are positioned between the inwardly extending arms of angle irons 17 which latter are secured to the inner surface of the cylindrical shell 10 of the kiln.

40 45 This construction is also utilized to provide the air passages 18 for the cooling air which passes into the passages successively as the kiln rotates and passes outwardly through the slots in the liners 11 as will hereinafter be described and inwardly through the clinker load indicated at 19 in Figure 7. This air constitutes the cooling air and also after passing through the hot clinkers 19 is preheated and is used as preheated air in the kiln in a well-known manner.

50 55 The liner structures 11 are shown in considerable detail in Figures 1, 2, 3 and 4, to which attention is now directed. Each liner has an arched top 20 which is provided with a plurality of slots 21 extending axially of the kiln and also axially of the arched liner. These slots taper inwardly, or in other words are enlarged inwardly, 60 so that any small clinker particles that pass into the slots will continue through the slots without any chance of wedging and thus without any chance of clogging the slots.

65 70 The liners are provided with axially extending cooling ribs 22, see Figure 2, which project inwardly and are thus positioned in the cooling air and assist in cooling the liners. In addition to this the liners are provided with opposed roughly triangular webs 23 which extend inwardly from the end walls 24 and project downwardly from the inner surface of the liners. The webs 23 are joined by the transverse portion 14 previously mentioned

which is provided with an opening or slot 25 for the reception of the bolt 12, see Figure 6, the head 26 of the bolt 12 resting upon the transverse member 14.

It will be seen from the construction thus far described that the bolt head 26 is positioned downwardly below the liner a considerable distance and is thus removed from the hottest portion of the liner. This construction greatly reduces the chance of the burning off of the heads of the bolts, for it will be seen that not only are the heads of the bolts positioned inwardly and spaced a considerable distance from the liners but also they are located directly in the cooling air stream. The bolts are provided with nuts 27 on the outer side of the cylindrical shell 10 of the kiln.

It is to be noted that the end walls 24 of the liners are apertured as indicated at 28 in Figure 4. This provides for the discharge of cooling air not only through the slots 21 of the liners but also from their end walls and into the space between successively axially positioned liners as shown in Figure 5. The liners are preferably provided with relatively narrow transversely extending, inwardly projecting webs 29.

Referring to Figure 7, it will be seen that fine clinker particles and clinker dust fall through the slots 21 into the air passages 18 and will collect in such air passages temporarily. The end wall 30 is provided with a plurality of openings of slots 31 on the trailing side of the air passages 18. These openings or slots 31 are extended peripherally of the recuperator section of the rotary kiln and as stated are on the trailing side of the air passages 18. It will be seen therefore that as the kiln rotates in the direction indicated in Figure 7 that the clinker particles tend to collect at the trailing side of the air passages and are blown outwardly through the openings 31. They may be led back into the kiln in any suitable manner, not shown, or may be completely discharged from the kiln.

It has been found that the kiln is very much more efficient and requires a lower air pressure than heretofore required due to the fact that voids are formed in the clinker load due to the falling out of the small clinker particles. These voids allow freer passage of air through the clinker load and thus the required air pressure is less. In addition to this all of the slots leading through the top wall of the liners are radially arranged and consequently there is no tendency to produce a whirling action in the recuperator section of the kiln. Further than this the liners are of relatively light weight and not as bulky as the previously known types of liners.

Other advantages result from the use of the liners as hereinabove described one of which is the relative freedom from abrasive material in the preheated air since there is no whirling action produced in the air discharged through the liners. The result of this is that there is less abrasion produced since there is less entrainment of abrasive particles.

While this invention has been described as applicable to a cement kiln, it is understood that the construction is equally applicable to lime kilns or kilns for other refractory materials.

5 Although this invention has been described in considerable detail, it is to be understood that such description is intended as illustrative rather than limiting as the invention may be variously embodied and is to be interpreted as claimed.

10 I claim:

1. A recuperator construction for a rotary kiln comprising a series of rings of arched, hollow liner members having roofs arched about an axis substantially paralleling the axis of the kiln and having a series of air discharge openings, an outer cylindrical shell, a series of webs extending longitudinally of said kiln and located between said liners and said shell and defining air supply passages, and an annular end wall closing the outer ends of said air passages, said annular end wall having openings therein for the discharge of small clinkers which have passed through the air discharge openings in said liner members, said last mentioned openings being relatively small as compared with the cross sectional area of said air passages, the openings in said end wall being located adjacent said shell and adjacent a corner of the several air passages, said kiln being designed to rotate in a direction such that the said corners are the trailing corners.

2. A recuperator construction for a rotary kiln comprising a series of rings of arched, hollow liner members having roofs arched about an axis substantially paralleling the axis of the kiln and having a series of air discharge openings, an outer cylindrical shell, a series of webs extending longitudinally of said kiln and located between said liners and said shell and defining air supply passages, and an annular end wall closing the outer ends of said air passages, said annular end wall having openings therein for the discharge of small clinkers which have passed through the air discharge openings in said liner members, said last mentioned openings being relatively small as compared with the cross sectional area of said air passages, the openings in said end wall being located adjacent said shell and adjacent a corner of the several air passages, said kiln being designed to rotate in a direction such that the said corners are the trailing corners, and said openings being elongated peripherally of said shell.
